(57) **CLAIM**

An ornamental design for a faucet head as shown and described.

DESCRIPTION

FIG. 1 is a top perspective view of an exemplary faucet head according to a new design;

FIG. 2 is a bottom perspective view thereof;

FIG. 3 is a right side view thereof;

FIG. 4 is a left side view thereof;

FIG. 5 is a front view thereof;

FIG. 6 is a back view thereof;

FIG. 7 is a top view thereof;

FIG. 8 is a bottom view thereof;

FIG. 9 is another left side view thereof and in a first pivot position; and,

FIG. 10 is another left side view thereof and in a second pivot position.

The portions depicted in broken lines form no part of the claimed design.
